ATTY.

UNITED STATES PATENT OFFICE.

THOMAS J. LESHER, OF LANSING, MICHIGAN, ASSIGNOR TO THE NORWICH NICKEL AND BRASS COMPANY, OF NORWICH, CONNECTICUT.

DESIGN FOR A DISPLAY-FRAME.

SPECIFICATION forming part of Design No. 33,110, dated August 21, 1900.

Application filed July 17, 1900. Serial No. 23,977. Term of patent 3 $\frac{1}{2}$ years.

To all whom it may concern:

Be it known that I, THOMAS J. LESHER, a citizen of the United States, residing at Lansing, in the county of Ingham and State of Michigan, have invented and produced a new and original Design for Display-Frames, of which the following is a specification, reference being had to the accompanying drawings, forming part thereof.

10 Figure 1 is a front elevation of a display-frame showing my new design, and Fig. 2 is a side elevation of the same.

As shown in the drawings, the leading or material features of my design are as follows:

15 An upright or standard *a* is mounted in a suitable base *b* and has mounted thereon three superimposed circular shelves *b'* *b''* *b'''* of gradually-decreasing diameter from the lowest to the highest of said shelves. Ex-
20 tending radially outward from the said upright from a point just above the base *b* are rods *c c c*, that are bowed upward and inward to points above the upper shelf *b'*, where they are joined to said upright by suitable clips *d*,
25 and the free upper portions of the said rods

are then curved outward, as at *c'*. Secured to the "bowed" portions of the rods *c* are horizontal bars *e*, each of which supports a number of clamps *e'*, adapted to receive and support a shoe or boot. Secured to each of 30 the bowed rods *c* near its lower portion is a substantially-semicircular rod *f*, whose lower end portion is bent downward and is supported by a base *f'*. Each of these rods *f* has mounted upon it at the point where it bends 35 downward a horizontal bar *f''*, with clamps *e'*. The top of the upright *a* terminates in an acorn-shaped ornament.

Having described my invention, what I claim as new, and desire to secure by Letters 40 Patent, is—

The design for a display-frame as herein shown and described.

In testimony whereof I have signed my name to this specification in the presence of 45 two subscribing witnesses.

THOMAS J. LESHER.
